MEANS FOR SECURING PRINTING PLATES
TO THEIR CYLINDERS UNDER TENSIONTheodore R. Ziebell, Milwaukee, Wis., assignor to
C. B. Cottrell & Sons Company, Westerly, R. I.,
a corporation of Delaware

Application November 2, 1951, Serial No. 254,565

7 Claims. (CL. 101—378)

1

This invention relates to means for securing printing plates to their cylinders under tension.

In plate securing means used in high speed rotary presses where the plate hooks are propelled along the cylinder grooves to and from their plate engaging positions by worm gears carried by the hooks and engaging the cylinder racks, the cylinder racks frequently become worn and broken because of the necessarily limited engagement of only one or two of the teeth of the worm gears with the teeth of the cylinder racks.

This invention is directed to plate tensioning means for overcoming these rack failures by providing a plate tension hook comprising coacting stationary and movable members; the stationary member having a row of teeth for extended engagement with the teeth of a cylinder rack to prevent endwise movement of the stationary member; the movable member, which carries the printing plate engaging jaw, being slidable along the stationary member to exert tension on the printing plate for securing it to its cylinder.

This invention is also directed to a plate tension hook having novel features of construction whereby the manually operated adjusting screw, which connects the stationary and movable members of the plate tension hook, is rotatably mounted against endwise movement in the movable member and has a screw threaded engagement with the stationary member.

This invention is also directed to a plate tension hook in which gearing is provided for operatively connecting the adjusting screw with a removable key or other suitable instrument.

A practical embodiment of my invention is represented in the accompanying drawings, in which

Fig. 1 represents a detail plane view showing a portion of a printing plate secured to its cylinder.

Fig. 2 represents a similar view on a much larger scale.

Fig. 3 represents a detail longitudinal section taken in the plane of the line 3—3 of Fig. 2;

Fig. 4 represents a detail cross section taken in the plane of the line 4—4 of Fig. 2;

Fig. 5 represents a detail cross section taken in the plane of the line 5—5 of Fig. 2;

Fig. 6 represents a side view of a key suitable for use in operating the movable hook member and for turning one of the locks which slidably hold the movable member in its cylinder groove.

Fig. 7 represents an edge view of the said key.

The grooved base on which the printing plates are to be secured under tension is shown as a plate cylinder 11 having spaced undercut spiral

2

grooves 12 provided along their bottoms with toothed racks 13.

The curved printing plate 14 is shown as provided with undercut recesses 15 in its back adjacent its marginal edges for the reception of the plate tension hook jaws to be hereinafter described.

The plate tension hook for securing the printing plate 14 on the cylinder 11 under tension is shown as comprising a stationary member 16 and a movable member 17 in which the stationary member is housed.

The stationary member 16 is shown as provided with a row of teeth 18 along its bottom for extended engagement with the teeth of the cylinder groove rack 13 to lock the stationary member against endwise movement along the cylinder groove 12 when the plate tension hook has been inserted into the said groove at the desired position along the same, adjacent the recesses 15 in the back of the printing plate 14.

The movable member 17 of the plate tension hook carries a plate engaging jaw 19 for securing the plate on the cylinder under tension. This movable member 17 has a longitudinal bottom groove 17* which houses the stationary member 16; the side walls of said groove slidably engaging the side walls of the stationary member.

The manually operated means for slidably holding the movable hook member 17 in its cylinder groove 12 is shown as a pair of double winged locks 20, 21, mounted near the ends of the said movable member and arranged to be turned into and out of the small grooves 22 along the side walls of the cylinder groove 12.

The turnable lock 20 is formed integral with the plate engaging jaw 19. The turnable lock 21 is shown as having an angular bore 23 for receiving the larger shank 24 of a suitable key 25 for turning the said lock into and out of its sliding engagement with the side grooves 22.

The turnable lock 20 of the combined jaw and lock 19, 20 may be turned into and out of sliding engagement with the side grooves 22 by manually turning the jaw 19. The usual spring pressed balls 26, 27 may be employed to frictionally engage the locks 20, 21 to yieldingly hold them in their withdrawn and extended positions.

The manually operated means for sliding the movable hook member along the stationary hook member, which is housed therein, is constructed, arranged and operated as follows:

An adjusting screw 28 operatively connects the two hook members 16, 17, the head of the said screw being rotatably mounted against endwise

movement in the movable member 17 and the threaded shank of the said screw being passed through and having a screw threaded engagement with the stationary member 16 of the said hook within said bottom groove 17*.

The adjusting screw 28 has integral therewith a bevel gear 29 which meshes with a bevel gear 30 whose shank is rotatably mounted in the enlarged portion of the axial bore 23 of the turnable lock 21. The upper end of this axial bore 23 is made angular for receiving the larger shank 24 of the key 25 for turning the lock 21 into and out of its sliding engagement with the side grooves 22. The bevel gear 30 is provided with a smaller axial bore 32 for receiving the smaller shank 33 of the key 25 which may be inserted through the angular bore 31 for turning the bevel gear 30.

In operation, the plate tension hooks are inserted into the cylinder grooves 12 in proper positions to cause the rows of teeth 13 of the stationary hook member 16 to bring the plate engaging jaws 19 into position to be engaged with the recesses 15 in the back of the printing plate 14. The jaw 19 of each of the plate hooks may then be turned to cause its double winged lock 20 to slidably engage the side grooves 22. The shank 24 of the key 25 may then be inserted into the angular bore 31 to turn the double winged lock 21 to also slidably engage the side grooves 22. The shank 33 of the key 25 may then be inserted into the angular bore 32 of the gear 30 to turn it and its meshing gear 29, which is fast on the adjusting screw 28, and thereby cause the screw, because of its threaded engagement with the stationary hook member 16, to slide the movable hook member 17 along the stationary hook member 16 to cause the jaw 19 to engage the recess 15 for exerting tension upon the printing plate 14 to secure it firmly on the cylinder 1.

It will be understood that while the plate holding means is herein shown and described in connection with a curved printing plate and a spirally grooved cylinder, the plate holding means may be employed in connection with plates and their bases of any character within the scope of this invention.

It is evident that various changes may be resorted to in the construction, form and arrangement of the several parts without departing from the spirit and scope of this invention and hence it is not intended to be limited to the particular embodiment shown and described herein.

What I claim is:

1. A cylinder having spaced grooves, a printing plate having recesses in its back, and a plate tension hook comprising a stationary member having means for locking it in a cylinder groove against endwise movement therein, a movable member having a longitudinal bottom groove housing the stationary member, a plate recess engaging tension jaw carried by the movable member, a screw located in said bottom groove and operatively connecting the two members, and a manually operated gearing for rotating the screw to slide the movable member along the stationary member housed therein in a direction to cause the tension jaw to secure the plate on the cylinder under tension.

2. A cylinder having spaced grooves, a printing plate having recesses in its back, and a plate tension hook comprising a stationary member having means for locking it in a cylinder groove against endwise movement therein, a movable member having a longitudinal bottom groove

10 housing the stationary member, a plate recess engaging tension jaw carried by the movable member, a screw located in said bottom groove and rotatably mounted against endwise movement in the movable member and threaded into the stationary member, a gear fast on said screw, and a manually operated meshing gear carried by the movable member for rotating the screw to slide the movable member along the stationary member housed therein in a direction to cause the tension jaw to secure the plate on the cylinder under tension.

3. A cylinder having spaced grooves, a printing plate having recesses in its back, and a plate tension hook comprising a stationary member having means for locking it in a cylinder groove against endwise movement therein, a movable member having a longitudinal bottom groove housing the stationary member and provided with two manually turnable locks for slidably holding the hook in its cylinder groove, a plate recess engaging tension jaw carried by one of the turnable locks, and a manually operated means operable through the other lock for sliding the movable member along the stationary member housed therein in a direction to cause the tension jaw to secure the plate on the cylinder under tension.

4. A cylinder having spaced undercut grooves provided with toothed racks, a printing plate having recesses in its back, and a plate tension hook comprising a stationary member having a row of teeth for extended engagement with one of said racks to lock the stationary member against endwise movement in the cylinder groove, a movable member having a longitudinal bottom groove housing the stationary member and provided with two manually turnable locks for slidably holding the hook in its cylinder groove, a plate recess engaging tension jaw carried by one of the turnable locks, and a manually operated means operable through the other lock for sliding the movable member along the stationary member housed therein in a direction to cause the jaw to secure the plate on the cylinder under tension.

5. A printing plate tension hook comprising a stationary member provided with means for locking it against endwise movement in a plate cylinder groove, a movable member having a longitudinal bottom groove housing the stationary member and provided with two manually turnable locks for slidably holding the hook in its cylinder groove, a plate recess engaging tension jaw carried by one of said turnable locks, and means operable through the other lock for sliding the movable member along the stationary member housed therein.

6. A printing plate tension hook comprising a stationary member provided with a row of teeth for locking it against endwise movement in a plate cylinder groove, a movable member having a longitudinal bottom groove housing the stationary member and provided with two manually turnable locks for slidably holding the hook in its cylinder groove, a plate recess engaging tension jaw carried by one of said turnable locks, and means operable through the other lock for sliding the movable member along the stationary member housed therein.

7. A printing plate tension hook comprising a movable member having a longitudinal bottom groove, a plate recess engaging tension jaw carried by the movable member, a stationary member housed in the said bottom groove and pro-

vided with a row of rack engaging teeth, and a manually operated screw located in said bottom groove and rotatably mounted in the movable member against endwise movement and having a screw threaded engagement with the stationary member for sliding the movable member along the stationary member housed therein.
